GOVERNOR APPARATUS

George W. La Salle, Canton, Ohio, assignor to
 Hercules Motors Corporation, Canton, Ohio, a
 corporation of Ohio

Application October 20, 1933, Serial No. 694,434

5 Claims. (Cl. 264—3)

The invention relates in general to governor apparatus adapted for association with means controlling the speed of rotation of a shaft, whereby the control means may be set so that the shaft will rotate at any of a plurality of speeds of rotation between stop and full speed, and so that at any setting of the control means and any consequent speed of rotation of the shaft, the governor apparatus will operate by a governor action to maintain the speed of rotation of the shaft within predetermined upper and lower limits with respect to the set speed.

More particularly the invention relates to governor apparatus of the foregoing general character, and which is adapted for use in connection with a compression ignition internal combustion engine utilizing preferably liquid hydrocarbon fuel, such as Diesel oil.

Such an engine is not provided with spark ignition, and consequently the only means of stopping such an engine is to cut off the flow of liquid fuel to the combustion chambers thereof.

When such an engine is used in connection with an industrial power unit, the operator of the same may be frequently absent from the engine, and it is desirable that the control means regulating the rate of flow of liquid fuel to the combustion chambers of the engine be adapted for variable setting to provide variable speeds of rotation of the engine crank shaft, between stop and full speed or full power, intermediate speeds of the engine preferably including an idling speed, and when the control means is set for any of the variable speeds of the engine, it is desirable that governor means be associated with the control means, and that the governor means operate to provide a governor action at any setting of the control means so as to maintain the speed of rotation of the engine crank shaft at the set speed, it being understood that the tendency of such an engine is to overspeed for any particular setting of the control means thereof.

It is moreover desirable that the governor apparatus for a relatively high speed compression ignition internal combustion engine be as compact as possible, be arranged for proper lubrication, and be of such construction and arrangement as to require governor weights or balls as light as possible, to minimize the space requirements for the operation of the governor weights or balls, and to avoid the setting up of heavy bearing loads during high speed operation of the same.

55 Governor apparatus available prior to the pres-

ent invention did not permit setting the control means at any of a number of different settings between two extreme positions, one of which stopped the engine and the other of which caused full speed or full power rotation of the crank 5 shaft of the same, and the intermediate positions providing for an idling speed of rotation and a plurality of intermediate speeds of rotation, and at the same time providing a governor action at each of the speed settings of the control means. 10

The objects of the present improvements include in general the provision of a governor apparatus operatively associated with a rotary shaft, means controlling the speed of rotation of the shaft, and means for setting the control 15 means, whereby the control means may be set, so that the shaft will rotate at any of a plurality of speeds of rotation between stop and full speed, and so that at any setting of the control means and any consequent speed of rotation of the shaft the governor apparatus will maintain by a governor action the set speed of rotation of the shaft.

The objects of the present improvements include in particular the provision of such a governor apparatus in combination with a compression ignition internal combustion engine and the fuel pump therefor, whereby the rate of flow of liquid fuel delivered by the fuel pump to the combustion chambers of the engine may be variably set for stopping the engine, and for running the engine at selected speeds between an idling speed and full speed or full power, and in which at any set speed, a governor action maintains the speed of rotation of the engine crank 35 shaft within predetermined limits with respect to the set speed.

Further objects of the present improvements include the provision of governor apparatus adapted for use in connection with a high speed 40 engine or the like, and in which the parts are so constructed and arranged as to have relatively small over-all dimensions, or in other words as to be compact.

Further objects of the present improvements 45 include the provision of governor apparatus adapted for high speed operation, and which includes centrifugally operated governor weights, and in which the parts of the apparatus are so constructed and arranged as to permit the use 50 of relatively light governor weights, thereby reducing bearing pressures in the apparatus to a minimum.

Further objects of the present improvements 55 include the provision of governor apparatus

of the foregoing description, and which is constructed and arranged for proper lubrication.

Further objects of the present improvements include the provision of improved details of construction and arrangement for certain of the parts of the governor apparatus and of the governor apparatus in combination with a compression ignition internal combustion engine.

The foregoing and other objects are attained by the improvements, apparatus, parts, combinations, and sub-combinations, which comprise the present invention, and the nature of which is set forth in the following general statement, and preferred embodiments of which, together with their mode of use are set forth in the following description, and which are particularly and distinctly pointed out and set forth in the appended claims forming part hereof.

The nature of the present invention may be described in general terms as including a rotary shaft, power drive means for the shaft, variable control means controlling the operation of the power drive means and adapted to be set so that the operation of the power drive means is stopped and/or is such that the rotary shaft rotates at any one of a plurality of speeds, control setting means operatively associated with the control means for varying the setting of the same, and governor means operatively associated with the control setting means and with the control means and operative by governor action to maintain the speed of rotation of the shaft within predetermined limits with respect to any speed normally corresponding to any particular setting of the control setting means.

The improved governor apparatus is preferably included in and/or combined with a compression ignition internal combustion engine as hereinafter set forth in greater detail, and the apparatus and engine also preferably include further novel improvements illustrated in the drawings and/or as hereinafter set forth.

A compression ignition internal combustion engine equipped and combined with the present improved governor apparatus is illustrated in the accompanying drawings forming part hereof, in which

Figure 1 is a side elevation view of a compression ignition internal combustion engine having a fuel pump equipped with the improved governor apparatus of the present invention;

Fig. 2, an enlarged transverse sectional view of the improved governor apparatus, as on line 2—2, Fig. 1, distant parts of the engine and fuel pump being removed;

Fig. 3, a similar enlarged transverse sectional view of the improved governor apparatus, as on line 3—3, Fig. 1;

Fig. 4, a fragmentary part side elevation and part longitudinal sectional view with portions broken away of the improved governor apparatus and portions of the fuel pump, distant parts of the engine being removed, and the improved governor apparatus being illustrated in longitudinal section as on line 4—4, Fig. 3;

Fig. 5, a view similar to Fig. 4, the improved governor apparatus being illustrated in longitudinal section as on line 5—5, Fig. 2;

Fig. 6, a view similar to Fig. 4, with different portions broken away;

Fig. 7, a further enlarged plan sectional view as on line 7—7, Figs. 4, 5, and 6.

Similar numerals refer to similar parts throughout the several views.

75 The compression ignition internal combustion

engine equipped with the present improved governor apparatus is indicated generally at 10 and as illustrated is a six cylinder, four stroke cycle, single action, high speed, compression ignition internal combustion engine, in which the air for combustion is obtained normally directly from the atmosphere, and in which separate quantities or charges of the preferred liquid hydrocarbon fuel, such as Diesel oil, are successively injected, by operation of a fuel pump indicated generally by 11, into the combustion chambers of the engine at successive timed intervals, one charge being injected into the combustion chambers of each cylinder during each four stroke cycle of the piston operatively mounted in the 15 cylinder.

The fuel pump 11 is operatively mounted on one side of the engine as shown in Fig. 1, and as illustrated is of usual construction and arrangement and includes a shaft 12, driven by 20 an operative connection with gearing contained in a gear housing 13 of the engine, the gears in the gear housing being driven by the engine crank shaft. The gears and crank shaft are not shown, and may be of a usual construction 25 and arrangement.

The fuel pump 11 includes a casing 14 in which plunger pistons, not shown, are operatively mounted, each in a pump cylinder, not shown, formed in the casing 14, one pump plunger piston and cylinder being provided for each cylinder of the engine.

The plunger pistons are actuated in a usual manner by cams on a cam shaft portion, not shown, of the shaft 12, the cam shaft portion 35 being located within a cam shaft chamber of the casing 14.

Each pump cylinder communicates with a discharge outlet 15 which communicatively connects with one end of a tube 16 the other end 40 of which communicatively connects with a pintle nozzle discharging into the combustion chambers of one of the engine cylinders.

The liquid fuel is supplied to the pump 11 through a main supply tube 17 in which an oil 45 cleaner 18 may be interposed ahead of the fuel pump 11.

The fuel pump is provided with the present improved governor apparatus indicated generally by 19, and the fuel pump also includes valve or 50 variable metering means for each fuel pump cylinder controlling the quantity of liquid fuel admitted to each pump cylinder from the main supply tube 17, and thus controlling the quantity of fuel in each charge pumped out of each pump 55 cylinder into its associated engine cylinder combustion chambers on the pressure stroke of the piston of the pump cylinder.

The fuel pump 11 furthermore includes a valve setting or throttle rod 20 which is operatively 60 associated with each of the valve means for each of the pump cylinders and which is arranged for reciprocation in normally horizontal opposite directions in the casing 14 of the fuel pump 11.

The rod 20, when displaced to its extreme position in the direction of the arrow S, in Figs. 4, 5, 6, and 7 actuates the valve means so as to shut off the flow of liquid fuel into the pump cylinders, and thus stops the engine. At the position of the rod 20 and associated parts as 70 illustrated in full lines in Figs. 4, 5, 6, and 7, the pump valve means are set to a position for permitting a flow of fuel into the pump cylinders at such rate as to cause the engine 10 to operate at a desired idling speed.

Displacement of the rod 20 in the direction of the arrow F actuates the pump valve means to increase the rate of flow of liquid fuel into the pump cylinders, the greater the displacement of the rod 20 in the direction of the arrow F, the greater the rate of flow of liquid fuel into the pump cylinders.

Accordingly the valve means of the pump cylinders may be termed control means determining the speed of operation of the engine, and the rod 20 may be termed a control means actuating member which is movable between two extreme positions, one of which is such that the control means are actuated to stop the engine or apparatus controlled by the control or valve means, and the other of which is such that the control means are actuated so as to run the engine at full speed, and intermediate positions of which include a setting which provides an idling speed for the engine, and provides for varying speeds thereof between the idling speed and the full speed.

Particularly in an industrial power unit where the operator may be frequently absent from the engine, as aforesaid, it is desirable that the control actuating member 20 be associated with governor means which permit a governor action at any setting of the control actuating means between the idling setting and the full speed setting, and also which permits a stop setting of the control actuating member 20.

The present improved governor apparatus 19 is associated with the pump and its throttle rod or control actuating member 20 so as to attain these and other objects of the invention.

The governor apparatus 19 preferably includes a casing indicated generally by 21 and which comprises walls forming a governor chamber 22, and which in the illustrated embodiment consists of two casing sections 23 and 23' secured to each other, and the casing section 23' being secured to the pump casing 14.

The governor casing section 23' includes an end wall 24 which abuts against the adjacent end wall 25 of the pump casing 14, and the governor drive end 26 of the pump shaft 12 extends through suitable apertures formed in the pump casing wall 25 and the governor casing wall 24, and preferably anti-friction bearing means indicated generally by 27 journal the shaft in the governor casing wall 24, and the governor drive end 26 of the pump shaft 12 terminates within the governor chamber 22.

A governor drive gear 28 is secured upon the governor drive end 26 of the pump shaft 12 within the governor chamber 22, and also within the governor chamber, a governor shaft 29 is journal mounted at opposite ends as by means of anti-friction bearing means indicated generally by 30 and 31, respectively, which are themselves respectively mounted in the governor casing end wall 24 and the opposite governor casing end wall 32.

The longitudinal axis of rotation of the governor shaft 29 is preferably parallel with the longitudinal axis of rotation of the pump shaft 12 and the governor shaft has secured thereon a driven pinion 33 which is located adjacent the anti-friction bearing means 30 and which is meshed with the governor drive gear 28, whereby rotation of the pump shaft 12 driven as aforesaid from the crank shaft of the engine, serves to rotate the governor shaft 29.

The governor shaft 29 has secured thereon, in

the illustrated embodiment adjacent the driven pinion 33, a spider 34 having sets of arms 35 and 35' respectively extending from diametrically opposite sides of the shaft 29, and governor weights 36 and 36' are pivotally mounted intermediate 5 their ends respectively on the opposite sets of spider arms 35 and 35', as by means of spider pins 37 and 37', the longitudinal axes of which are parallel, and which are spaced at equal distances from the longitudinal axis of the governor shaft 29, and lie in a plane normal to the longitudinal axis of the shaft 29.

The governor weights 36 and 36' are of a desired shape, and are substantially identical with each other, and have their centers of gravity 10 located at equal distances from the longitudinal axes of the pins 37 and 37' beyond the outer extremities of the sets of spider arms 35 and 35'.

The governor weights 36 and 36' include respectively sleeve actuating tongues 38 and 38' 20 which extend toward the governor shaft 29, the tongues 38 and 38' being located between the spider pins 37 and 37' and the governor shaft 29.

The governor weights 36 and 36' also include 25 at their inner extremities stop tongues 39 and 39' which abut against opposite stop faces on the spider hub 40 and limit the outward movement of the weights 36 and 36' under the action of the centrifugal forces set up therein by rotation 30 of the shaft 29.

A sleeve 41 is slidably mounted on the governor shaft 29 between the spider 34 and the outer bearing means 31 for the governor shaft 29, and the end face 42 of the sleeve 41 adjacent the tongues 38 and 38' of the governor weights 36 35 and 36' is abuttable by the outer extremities of the tongues 38 and 38', and the sleeve 41 is longitudinally movable on the shaft 29, and is moved by or moves the weights 36 and 36' during operation of the governor between and including 40 idling speed and full speed of the engine, as is hereinafter set forth in greater detail.

Intermediate its ends, the sleeve 41 has rotatably mounted thereon a ring 43, the mounting of the ring 43 on the sleeve 41 being preferably as 45 illustrated by means of an anti-friction bearing 44.

The governor apparatus 19 furthermore includes a yoke lever pivoting tube shaft 45 which is secured at its ends in the opposite side walls 46 50 and 47 of the governor casing section 23, and which is located at one side of, and as illustrated, normally below the governor shaft 29, the longitudinal axis of the tube shaft 45 extending at right angles to the direction of the longitudinal 55 axis of the governor shaft 29.

A movable member or yoke lever 48 is pivotally mounted at one end 49 on the tube shaft 45, and the yoke lever end 49 as illustrated is the lower end of the yoke lever 48.

The yoke lever 48 has formed therein a central opening 50, and the governor shaft 29, the sleeve 41, and the ring 43 rotatably mounted on the sleeve 41 as aforesaid, extend through and/or are located within the central opening 50 of the 65 yoke lever 48.

The yoke lever 48 includes side members 51 and 51' comprising in part the boundary members for the opening 50 and the yoke side members 51 and 51' are located on opposite sides of 70 the shaft 29, the sleeve 41 and the ring 43.

The ring 43 has formed in its outer peripheral surface an outwardly opening annular groove 52 and pins 53 and 53' have their outer ends respectively secured in the yoke side members 51 75

and 51' and have their inner ends extending into the ring groove 52.

At the upper corner of the yoke lever 48 opposite the outer end of the rod 20, connector ears 54 and 54' are provided and a longitudinally adjustable link means 55 is pivotally connected at its outer end with the ears 54 and 54', as by pin means 56, and the link means 55 is pivotally connected at its inner end with the outer extremity 10 of the rod 20 as by pin means 57.

At the other upper corner of the yoke lever 48, connector ears 58 and 58' are provided and the connector ears 58 and 58' are connected by slot and pin means 59 with one end of a telescoping spring support member 60, the other end of which telescopes with one end of another telescoping spring support member 61, and the telescoping members 60 and 61 are connected to each other by a tension spring 62 through which the telescoping members extend, so that in the event the spring 62 should break, the parts thereof will not drop onto the other parts of the governor apparatus.

The governor apparatus 19 furthermore includes a control actuating member setting shaft 63 which is parallel to the tube shaft 45 and is located above the governor shaft 29, and is journalled in the opposite side walls 64 and 65 of the governor casing section 23'.

Opposite the yoke lever ears 58 and 58', a crank arm 66 is secured upon the shaft 63 and the outer end of the crank arm 66 is pivotally connected by pin means 67 with the adjacent end of the telescoping spring supporting member 61.

The shaft 63 extends beyond the outer side of the casing section 23' and has secured thereon a control setting lever 68 which is preferably associated with stop means indicated generally by 69 for limiting the high speed setting of the fuel pump control valves.

Preferably a compression spring 70 is interposed between the upper end of the yoke lever 48, and an externally threaded adjustable screw plug 71 screwed in an internally threaded bore formed 45 in the governor casing wall 32, the upper end of the yoke lever 48 and the plug 71 preferably having oppositely opening sockets formed therein into which the opposite ends of the compression spring 70 extend.

The operation of the improved governor apparatus 19 combined as aforesaid with the engine 10 and its fuel pump 11, is as follows:

As aforesaid, the governor apparatus parts as illustrated in Figs. 2, 3, 4, 5, 6, and 7 are in their several relative positions by which idling speed of the engine is obtained.

The control setting lever 68 may be operatively connected with usual sector and latch means, not shown, for maintaining the lever and the parts controlled thereby at any set position.

As best shown in Figs. 4 to 6 inclusive, in the idling setting of the governor apparatus parts, the tendency of the governor weights 36 and 36' to move the sleeve 41 and the yoke lever 48 towards the casing wall 32 is opposed by the spring 70, which is adjusted so as to normally maintain the yoke arm 48 so that the pin of the pin and slot means 59 is midway between the ends of the slot thereof, and consequently a slight increase 65 in the speed of the engine beyond the idling speed will cause the weights 36 and 36' to move outwardly and will slightly advance the control lever 48 towards the wall 32 and will thus move the rod 20 in the direction of the arrow S and 70 slightly decrease the rate of flow of fuel and 75

slow down the engine speed to the idling speed; and on the other hand a slight decrease in the speed of the engine will permit the spring 70 to move the yoke arm 48 towards the fuel pump and cause the weights 36 and 36' to move inwardly and the rod 20 will be moved in the direction of the arrow F and slightly increase the rate of flow of fuel and the speed of the engine to the idling speed, all of which may be termed a governor action at the particular idling speed 10 setting.

In the idling speed setting, the tension spring 62 has no tension load thereon, and with respect to movements thereof towards the casing wall 32 is in effect a solid member. Consequently for 15 stopping the engine the control setting lever 68 need only be rotated a slight distance counter-clockwise, as viewed in Fig. 6, so as to move the yoke lever arm 48 and the rod 20 connected thereto to a position in the direction of the arrow S such that the flow of all liquid fuel through the fuel pump 11 is stopped, and consequently the engine will stop.

For higher speed operations of the engine, the control setting lever 68 is swung in a clockwise 25 direction as viewed in Fig. 6 to any intermediate speed setting or the maximum high speed setting thereof, and by such clockwise movement of the control setting lever 68, the spring 62 will first be extended by tension loading and the 30 yoke arm 48 will then be pulled in the direction of the arrow F, and the rod 20 will be moved in the direction of the arrow F to the desired setting; and at any such settings, governor action of the apparatus will be obtained by reason of the tension loading of the spring 62 permitting slight swinging to and fro of the yoke lever arm 48 during governor action of the apparatus.

As shown in the drawings, the governor apparatus is exceedingly compact, and the 40 governor casing is adapted for containing a supply of lubricant for properly lubricating the several parts.

Also as shown in the drawings, the higher the speed setting of the apparatus, the closer the 45 centers of gravities of the governor weights are to the axis of the governor shaft, thus maintaining at a minimum the bearing loads in the apparatus during high speed operation thereof.

I claim:

1. In governor and control apparatus and the like, a movable member adapted for operative connection with variable control means and the like, a rotary shaft, centrifugally actuated means operatively mounted on the shaft and associated with the movable member so as to move and permit movement of the member when the speed of rotation of the shaft varies between predetermined limits, movable control setting means, and slot and pin means and resilient means connected with each other and connecting the movable member with the movable control setting means and resilient means urging the movable member in one direction.

2. In governor and control apparatus and the like, a movable member adapted for operative connection with variable control means and the like, a rotary shaft, centrifugally actuated means operatively mounted on the shaft and associated with the movable member so as to move and permit movement of the member when the speed of rotation of the shaft varies between predetermined limits, movable control setting means, and slot and pin means and resilient tension means connected with each other and connecting 75

the movable member with the movable control setting means and resilient means urging the movable member in one direction.

3. In governor and control apparatus and the like, a pivotally movable lever adapted for operative connection with variable control means and the like, a rotary shaft, centrifugally actuated means operatively mounted on the shaft and associated with the lever so as to pivotally move and permit movement of the lever when the speed of rotation of the shaft attains predetermined limits, movable control setting means, and slot and pin means and resilient means connected with each other and connecting the movable control setting means with the lever and resilient means urging the movable lever in one direction.

4. In governor and control apparatus and the like, a pivotally movable lever adapted for operative connection with variable control means and the like, a rotary shaft, centrifugally actuated means operatively mounted on the shaft and associated with the lever so as to pivotally move and permit movement of the lever when the speed of rotation of the shaft varies between

predetermined limits, movable control setting means, and slot and pin means and resilient tension means connected with each other and connecting the movable control setting means with the lever and resilient means urging the movable lever in one direction.

5. In governor and control apparatus and the like adapted for controlling the operation of a compression ignition internal combustion engine so as to permit idling speed operation and selective governor controlled variable speed operation thereof, a movable member adapted for operative connection with variable control means, governor means associated with the movable member so as to move and permit movement of the member during operation of the governor means, movable control setting means, oppositely spaced slot and pin means and resilient means connected with each other and interposed between and connecting the movable member with the movable control setting means, and resilient means urging the movable member in one direction.

GEORGE W. LA SALLE. 25
